US00D967274S

(12) United States Design Patent (10) Patent No.: US D967,274 S
(45) Date of Patent: * Oct. 18, 2022

(54) GAMING MACHINE

(71) Applicant: IGT, Las Vegas, NV (US)

(72) Inventors: Jean-Pierre Legras, Carson City, NV (US); Charles Johnson, Reno, NV (US)

(73) Assignee: IGT, Las Vegas, NV (US)

() Term: 15 Years

(21) Appl. No.: 29/806,514

(22) Filed: Sep. 3, 2021

Related U.S. Application Data

(62) Division of application No. 29/708,589, filed on Oct. 8, 2019, now Pat. No. Des. 931,941.
